UNITED STATES PATENT OFFICE.

ANDREW A. SEBULA, OF SOUTH MANCHESTER, CONNECTICUT.

PERMUTATION-LOCK.

1,152,231.

Specification of Letters Patent. Patented Aug. 31, 1915.

Application filed May 26, 1915. Serial No. 30,568.

To all whom it may concern:

Be it known that I, ANDREW A. SEBULA, a subject of the Emperor of Austria-Hungary, residing at South Manchester, in the county of Hartford and State of Connecticut, have invented certain new and useful Improvements in Permutation-Locks, of which the following is a specification.

This invention relates to certain new and useful improvements in permutation locks.

The primary object of this invention is the provision of a casing lock adapted for securing a keeper by means of a permutation controlled locking bolt adapted to be released by a specially designed form of releasing means, thereby preventing a retracting of the bolt by a person unfamiliar with the lock and even after the proper manipulation of the permutation members.

A further object of the device is the provision of a lock having a normally projected bolt retractable only upon the proper setting of permutation members accompanied by the separate actuation of a safety catch for the bolt, the said device being readily tripped as well as released by a person familiar with the operation of the lock.

For accomplishing these objects, a permutation device is arranged adjacent the normally projected bolt and a turn device for retracting the bolt when the permutation members are properly positioned is prevented from operation by a bolt engaging catch which is tripped into engagement with the bolt when the latter is projected and is also releasable upon the proper manipulation of the said retracting means, the manner of operating the same being difficult to ascertain by any person unfamiliar with the lock mechanism.

With these general objects in view and others that will appear as the nature of the invention is better understood, the same consists in the combination and arrangement of parts hereinafter more fully described, illustrated in the accompanying drawings, and pointed out in the appended claims.

In the drawings forming a part of this application and in which like-designating

characters refer to corresponding parts throughout the several views, Figure 1 is a front elevation of the lock detached. Fig. 2 is a view of the lock with the rear plate of the casing removed and with the elements 55 in their locked position. Fig. 3 is a similar view partially broken away with the permutation members and the bolt engaging catch in their releasing positions. Fig. 4 is a similar view with the bolt retracted. Fig. 5 is 60 a view similar to Fig. 3 with the retracting device as normally positioned and about to trip the bolt engaging catch, the latter being shown by dotted lines in its tripped position. Fig. 6 is a longitudinal sectional 65 view taken upon line VI—VI of Fig. 5. Fig. 7 is a transverse sectional view taken upon line VII—VII of Fig. 4. Fig. 8 is a sectional view taken upon line VIII—VIII of Fig. 3, and Fig. 9 is a detail view of the 70 bolt releasing means and with the adjacent portion of the casing shown in section.

Referring more in detail to the drawings, a casing 10 is provided for the lock mechanism having a removable rear plate 11, 75 while the front plate 12 of the casing is provided with a keeper receiving opening 13. A locking bolt 14 is slidably mounted in brackets 15 within the casing 10 and is normally held projected over the keeper 80 opening 13 by means of a spring 16 which connects the forward one of the brackets 15 with a flat plate extension 17 upon its inner end, the outer edge 18 of the said extension acting as a stop for engaging the inner 85 bracket 15 to limit the extent of projection of the said bolt.

The front plate 12 of the casing is provided with a dial 19 and a shaft 20 is centrally journaled therethrough, and extends 90 through the casing being journaled in the casing and in a bearing plate 21 mounted therein. The shaft 20 is provided with a turn knob 22 exteriorly of the front plate 12, while a star indicating wheel 23 is 95 mounted upon the shaft 20 adjacent thereto and overlying the dial 19 whereby the desired extent of rotations of the shaft 20 may be ascertained.

The shaft 20 is provided with outer and 100

inner permutation members 24 and 25 respectively in the form of gears and having their toothed peripheries 26 lying in the retracting path of movement of the bolt extension 17 whereby the beveled inner end 27 of the said extension will engage the teeth 26 of the two permutation members in the event that the bolt is partially retracted during the normal locking position 10 of the said permutation members. Each of the said members 24 and 25 is provided with an open slot 28 through its peripheral rim and it will be apparent that when the said slots 28 of both of the permutation members 15 are brought into direct alignment with the bolt plate 17, the bolt upon being retracted will allow the said extension 17 to freely pass through the said slots 28 and whereby the permutation members will offer no obstruction 20 to the unlocking of the bolt. A dog 29 is pivoted to the bearing plate 21 and has its angular end 30 ratchetingly engaging the teeth 26 of the inner permutation member 25 whereby the said member 25 may 25 only revolve in one direction, being restrained by the dog member 30 from revolving in an opposite direction. The permutation member 24 is secured upon the shaft 20 and is provided with an inwardly 30 extending pin 31 having a path of movement within the plane of an interrupted hub 32 carried by the adjacent face of the other permutation member 25 which latter member is freely journaled upon the said shaft 35 20. The hub 32 has an inclined free face 33 upon which the pin 31 is adapted to ride when the member 24 is revolved in one direction and at which time also the dog member 30 prevents a rotation of the member 25. 40 When the member 24 is revolved in an opposite direction, the pin 31 engages the squared end 34 of the hub 32 and carries the other member 25 around with the same and in which direction the dog member 30 freely 45 ratchets over the teeth of the said member 25. An expansion spring 35 is arranged between the plate 21 and the adjacent face of the permutation member 25 which resiliently returns the member 25 to its normal 50 position with respect to the other permutation member 24 after the pin 31 has completed its travel over the hub face 33. It will thus be evident that the permutation knob 22 is first turned in the direction indicated by the arrow in Fig. 1 for accurately 55 positioning the slot 28 of the inner permutation member 25 in releasing alignment with the bolt plate 17, the said member 25 thus moved in the direction indicated by the 60 arrow in Fig. 2, and having thus so positioned this member 25, the knob 22 is then turned in a reverse direction until the slot 65 28 of the outer permutation member 24 is

likewise positioned in alignment with the bolt extension 17, it being understood that 65 such adjustments are made to agree with the predetermined registering of certain teeth of the indicating wheel 23 with points upon the dial 19.

A connecting catch 36 is slidably mounted 70 within a bracket 37 within the casing 10 being normally influenced to project obstructingly inwardly of the adjacent side shoulder 38 of the bolt 14 by means of a spring 39 connecting an angular end 40 of the said 75 catch with the inner bracket 15 heretofore referred to. A spring plate 41 incloses the said angular end 40 and is provided with a depending lug 42 adapted to connect behind a shoulder 43 of the catch 36, when 80 the said catch is in its retracted releasing position as illustrated in Fig. 5, while a release of the catch 43 allows the spring 39 to project the catch 36 to its bolt engaging position as illustrated in Fig. 2. 85

A bolt retracting and latch actuating means is provided consisting of a turn handle 44 arranged upon the front plate 12 of the casing and having an inwardly projecting post 45 journaled in the casing side, 90 while a latch 46 is pivoted as at 47 to the said post and is normally retained elevated by means of a spring 48. The inner end of the spring 41 is inwardly turned as at 49 being V-shaped and terminating in a point 95 50, while a stepped stop lug 51 is positioned upon the side of the casing and lies adjacent the spring end 49.

With the catch 36 released as shown in Fig. 5, a turn of the handle 44 in the direction indicated in Fig. 1, moves the latch 46 with its beveled reduced end 52 between the spring end 49 and stop lug 51, thereby separating the said members sufficiently to release the lug 42 from its engagement with 100 the catch shoulder 43, thus allowing the catch to move to its engaging position, as shown in Fig. 2. After this release of the catch 36 the latch 46 will spring beneath and ratchet past the catch end 40 and may 105 continue this movement and in a similar manner pass beneath the arm 53, of the bolt 14, the latch 46 being slightly depressed by the said arm and engaging the lower beveled end 54 thereof. The elements will then 110 be positioned as illustrated in Fig. 2 which is the normal locked position of the bolt by both the permutation members as well as the catch 36. 115

It will be understood that a staple 55 or 120 any other desired form of keeper is adapted to be positioned through the front plate opening 13 of the casing which will be engaged by the locking bolt 14 as illustrated in Fig. 6. When desired to release the 125 keeper, the elements being found as illus- 125

trated in Fig. 2, the permutation members are operated by the knob 22 in the manner heretofore set forth to their releasing positions as shown in Fig. 3. The handle 44 is then turned for ratcheting the latch 46 beneath the spring end 49 and the catch end 40. A slight reverse movement of the handle 44 then engages the latch 46 with the catch end 40 and retracts the same until the lug 46 automatically engages the catch and retains the same retracted and in which position the stepped shoulder 56 of the stop lug 51 prevents a further reverse movement of the latch 46 all as illustrated in Fig. 3. The handle 44 then continues its movement further for moving the latch 46 beneath the bolt arm 53 and after passing the said arm, the handle 44 may be moved in a reverse direction which will engage the latch 46 with the said arm 53 which will thereby retract the bolt as best illustrated in Fig. 4.

It will be understood that the present device is adapted for use not only in connection with the form of staple keeper 15, but may be readily arranged to engage the usual form of door keeper (not shown) by projecting the locking bolt 14 through an opening in the adjacent side of the casing 10.

The form of device now set forth may be readily employed in connection with mail bags and strap locks and other similar devices, and it will be seen that it is necessary for a successful operation of the lock that the operator be familiar not only with the correct combination for the permutation members, but also with the required movements of the catch releasing means actuated by the handle 14.

While the form of the invention herein shown and described is what is believed to be the preferred embodiment thereof, it is nevertheless to be understood that minor changes may be made without departing from the spirit and scope of the invention as claimed.

What I claim as new is:

1. A lock comprising a casing, a locking bolt slidably positioned therein, a shaft journaled in the said casing, an operating knob upon the outer end of the said shaft, a peripherally toothed permutation gear secured upon the said shaft and having a side slot therein positioned in receiving alinement with the said bolt when arranged in predetermined position, a similar inner permutation gear journaled upon the said shaft in the path of movement of the said bolt and provided with a similar side slot therein, an interrupted hub secured to the said journaled gear and having an inclined face adjacent the companion gear, a fixed pin upon the first-named gear having a path of movement in the same plane as the said hub, a ratcheting dog for the said journaled gear, a normally projected engaging catch for the said bolt, retaining means for the said catch when released, combined tripping and setting means for the said catch and retracting means for the said bolt.
2. A lock comprising a casing, a locking bolt slidably positioned therein, a shaft journaled in the said casing, an operating knob upon the outer end of the said shaft, a peripherally toothed permutation gear secured upon the said shaft and having a side slot therein positioned in receiving alinement with the said bolt when arranged in predetermined position, and a reversely operable similar permutation gear journaled upon the said shaft and provided with a similar side slot adjustable in receiving alinement with the said bolt when in predetermined relation, a normally projected engaging catch for the said bolt, retaining means for the said catch when released, and combined tripping and setting means for the said catch and retracting means for the said bolt.
3. A lock comprising a casing, a locking bolt slidably positioned therein, a shaft journaled in the said casing, an operating knob upon the outer end of the said shaft, a peripherally toothed permutation gear secured upon the said shaft and having a side slot therein positioned in receiving alinement with the said bolt when arranged in predetermined position, a similar inner permutation gear journaled upon the said shaft in the path of movement of the said bolt and provided with a similar side slot therein, an interrupted hub secured to the said journaled gear and having an inclined face adjacent the companion gear, a fixed pin upon the first-named gear having a path of movement in the same plane as the said hub, a ratcheting dog for the said journaled gear, a normally projected engaging catch for the said bolt, retaining means for the said catch when released, combined tripping and setting means for the said catch, and retracting means for the said bolt.
4. A lock comprising a normally projected locking bolt, a permutation controlling means for said bolt, a slidable catch normally positioned in the path of movement of the said bolt, and having an angularly projecting engaging end, a retaining spring engageable and overlying the said catch end and having an inwardly projecting V-shaped end, a stepped stop lug positioned opposite the said V-shaped end, a tensioned pivotally mounted releasing latch having a line of movement between the said V-shaped end and stop lug and operatively engageable with the said catch end when swinging in one direction.
5. A lock comprising a normally projected locking bolt, a permutation controlling means for the said bolt, a slidable catch

normally positioned in the path of movement of the said bolt and having an angularly projecting engaging end, a retaining spring engageable and overlying the said catch end and having an inwardly projecting V-shaped end, a stepped stop lug positioned opposite the said V-shaped end, and a tensioned pivotally mounted releasing latch having a line of movement between the 10 said V-shaped end and stop lug and operatively engageable with the said catch end

when swinging in one direction, a side arm carried by the said bolt having a beveled end positioned within the swinging line of travel of the said latch, an operating handle 15 for the said latch, and a keeper means for the said locking bolt.

In testimony whereof I affix my signature.
ANDREW A. SEBULA.
